CLAIM

The ornamental design for a chuck for lifting steel metal, as shown and described.

DESCRIPTION

FIG. 1 is a left side view of a chuck for lifting steel metal showing my new design;

FIG. 2 is a right side view thereof;

FIG. 3 is a front view thereof;

FIG. 4 is a rear view thereof;

FIG. 5 is a top plan view thereof;

FIG. 6 is a bottom plan view thereof;

FIG. 7 is a cross-sectional view taken along line A—A in FIG. 3; and,

FIG. 8 is a cross-sectional view similar to FIG. 7 with the chuck in an alternate position.
